UNITED STATES PATENT OFFICE.

ADAM H. HAFLEY, OF ASHLEY, ILLINOIS, ASSIGNOR OF ONE HALF TO
PHIL. A. CARTER, OF SAME PLACE.

OSCILLATING ENGINE.

SPECIFICATION forming part of Letters Patent No. 314,932, dated March 31, 1885.

Application filed May 10, 1884. (No mod. & l.)

To all whom it may concern:

Be it known that I, ADAM H. HAFLEY, a citizen of the United States, residing at Ashley, in the county of Washington and State of

Illinois, have invented certain new and useful Improvements in Oscillating Engines; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 Figure 1 of the drawings is a side view of my device. Fig. 2 is a plan view of the same. Fig. 3 is a vertical transverse sectional view of the cylinder. Fig. 4 is a vertical longitudinal sectional view of the same, and Figs. 5 and 6 20 are detail views.

This invention has relation to improvements in that class of oscillating steam-engines in which reversing mechanism is used, and a steam-chest having a flat truly-planed side 25 provided with ports to register with similar ports in an oscillating steam-cylinder, the said cylinder also having a plain engaging side, and the ports so arranged as to be readily converted into receiving and exhaust ports; and 30 the invention consists in the construction and novel arrangement of devices, as will be hereinafter more fully set forth, and particularly pointed out in the claim appended.

In the accompanying drawings, A represents the frame of an oscillating steam-engine 35 having formed in it the proper vertical bearings a and a' for the horizontal shaft B, which carries the crank-wheel b immediately outside of the bearing a .

40 a^2 is an arm of the frame A, extending backward from the bearing a at right angles to the shaft B, and a^3 is an arm curving upward and outward from the frame A at any proper point below the arm a^2 , and having at its end the vertical bearing a^4 , parallel to the outer 45 surface of said arm and to the crank-wheel b.

C is the steam-chest fixed to the arm a^2 at a proper distance to the rear of the crank-wheel, and provided with a flat surface, c , in which 50 its ports open, and which lies in the same vertical plane as the outer surface of the arm a^2 .

c' is a longitudinal partition dividing the steam-chest into equal and similar chambers, c^2 and c^3 , respectively, above and below said partition.

55 c^4 is a vertical bearing formed in the surface c and partition c' , of the same height as and fellow to the bearing a^4 .

D and d are ports in the chamber c^2 , situated immediately above the partition c' , and 60 opening into the front and rear ends of said chamber respectively. E and e are similar ports for the front and rear ends of the chamber c^3 , situated immediately below the partition c' .

65 F is the cylinder having the flat surface f , equal in size to and fitting closely against the surface c of the cylinder. The cylinder is pivoted to the bearings a^4 and c^4 by the studs or trunnions f' and f^2 , respectively, which 70 stand centrally and at right angles, the latter from the surface f , and the former from the opposite side of the cylinder.

75 f^3 is a spiral spring surrounding the trunnion f' , between the bearing a^4 and the cylinder, and serving to press the latter against the steam-chest, and render the surfaces c and f steam-tight.

80 f^4 and f^5 are ports in the central longitudinal line of the surface f , opening in that surface from the front and rear ends of the cylinder respectively. The ports f^4 and f^5 are at such a distance from the trunnion f , lying between them, that as the cylinder oscillates the former will successively pass over the ports D 85 and E, in the upper and lower chambers, respectively, and the latter over the ports d and e .

85 f^6 is the piston, and f^7 the piston-rod, connected to the crank-wheel b by the wrist-pin f^8 .

90 G is a vertical pipe opening into the top of the upper chamber, c^2 , and provided with the escape or exhaust cock g . H is a similar pipe opening into the bottom of the lower chamber, c^3 , and provided with a similar cock, h .

95 I is a horizontal steam-pipe joining the pipe G at i , between the cylinder and the exhaust-cock g , and J is a pipe extending vertically downward from I for a sufficient distance and then bending at right angles and joining the pipe H at j , between the cylinder and the exhaust-cock h .

- z' is a throttle-valve in the steam-pipe I, at any proper point between the pipes J and G, and j' is a similar valve at any proper point in the pipe J.
- 5 K is the boiler, to which the steam-pipe I is attached at k . k' is a pipe passing from said boiler and coiled longitudinally in the water-tank L, and k^2 is a cock between said tank and the boiler.
- 10 L is a feed-water-heating tank formed of two equal and similar end portions united so as to be water-tight by the flanges $l l$ and bolts $l' l'$, &c., and containing the coiled pipe k' , the end of which opens within said tank.
- 15 l^2 is a plug in one end of the tank, which is removed when it becomes necessary to refill the same.
- l^3 is a feed-water pipe connecting the tank and boiler, and controlled by the cock l^4 between them.
- 20 The operation of the different parts of the mechanism is as follows: It being desired to run the crank-wheel b forward, the throttle z' and escape-cock h are closed, and the throttle j' and cock g opened. Steam will then enter the cylinder, when it begins to oscillate by way of the pipe J, lower chamber, c^3 , and ports E and e of the same acting as steam-ports, and the cylinder will exhaust by way of the ports 25 D and d and the upper chamber, c^2 , through the cock g , the crank-wheel b at the same time being drawn forward. Upon closing the throttle j' and cock g and opening the throttle i' and cock h' the steam will enter the upper 30 chamber, c^2 , the ports D and d of which act in this case as steam-ports. The exhaust will take place through the ports E and e , the lower chamber, c^3 , and cock h , and the crank-wheel b will reverse. It must be observed 35 that when the cylinder takes steam from the port at one end of one chamber it exhausts by

the port at the other end of the other chamber, and the reverse.

When it is desired to make use of the tank L, the cock k^2 of the pipe k' is opened, allowing the steam to escape from the open end thereof into the water in said tank and heat the same. When this is accomplished, the cock k^2 is closed, and the cock l^4 in the pipe l^3 is opened to feed the boiler; or the cock l^4 may 45 be entirely and the cock k^2 partially opened, thus admitting constantly just sufficient steam to keep the water at a proper temperature while being fed to the boiler.

I am aware that it is not new to arrange a 55 spring upon one of the trunnions of a steam-chest to provide for wear caused by an oscillating steam-valve, and keep the parts tightly in engagement with each other, and therefore claim only the devices of the specific construction hereinafter pointed out.

Having thus described my invention, what I claim, and desire to secure by Letters Patent, is—

In an oscillating steam-engine, the combination, with the steam-chest having the bearing c^4 , of the arm f^2 , the upwardly and forwardly curved arm a^3 , the steam-cylinder having the trunnions adapted to be supported by the said bearings, and the spring f^3 , arranged 65 upon the trunnion f^4 , and engaging the inner side of the said curved arm a^3 , to keep the cylinder pressed tightly against the steam-chest and form a steam-tight joint therewith, substantially as specified.

75 In testimony whereof I affix my signature in presence of two witnesses.

ADAM H. HAFLEY.
